UNITED STATES PATENT OFFICE.

JOHN W. BIRDSONG, OF COHAY, MISSISSIPPI.

COMBINED RAIL CLAMP AND CHAIR.

1,196,423.

Specification of Letters Patent. Patented Aug. 29, 1916.

Application filed February 19, 1916. Serial No. 79,417.

To all whom it may concern:

Be it known that I, JOHN W. BIRDSONG, a citizen of the United States, residing at Cohay, in the county of Smith and State 5 of Mississippi, have invented certain new and useful Improvements in Combined Rail Clamps and Chairs; and I do hereby declare the following to be a full, clear, and exact description of the invention, such as will 10 enable others skilled in the art to which it appertains to make and use the same.

The object of this invention is to provide a combined rail clamp and chair, that will effectively hold the rail against creeping and will admit of the rail clamp being held in 15 operative position without the use of spikes, and will also admit of the strain caused by the vibration of the rails during the passage of running stock thereover being equally distributed throughout the chair and clamp 20 and relieve the retaining means for the clamp from considerable strain.

Another object of the invention is to admit of the rail being placed in operative position on the chair or removed therefrom, expeditiously.

Other objects will appear and be better understood from that embodiment of my invention of which the following is a specification, reference being had to the accompanying drawings forming a part thereof, in which:

Figure 1 is a transverse section taken through one of the rails of a track, and 35 showing the rail resting on the improved chair and clamped to the chair by the clamp, Fig. 2 is a top plan view of Fig. 1, Fig. 3 is a reverse plan view of Fig. 2, Fig. 4 is a detail perspective view of the under side of 40 the clamping member.

Referring to the drawings more in detail, the numeral 1 designates a rail chair, provided at one end thereof with a raised portion 2, which forms a seat for the base 45 flange 3 of the rail 4. The raised portion 2 has its upper surface provided, at one end thereof, with a rail base-engaging flange 5, adapted to engage over the base flange 3 of the rail and assist in holding the rail in operative position. The opposite end of the 50 chair 2 is provided with a pair of openings 6 adapted to receive spikes for securing the chair to a tie. The portion 2 has that end which is opposite the end which has the 55 flange 5 formed thereon undercut, to provide the flange 7.

Pivottally associated with the rail chair 1 at a point adjacent the raised portion 2 is a rail clamp 9, which has pivotal connection with the chair 1 by means of the pivot pin 60 10, which extends through the clamp 9 and the chair 1 at one end of the clamp, as shown in Figs. 1 and 2 of the drawings. The clamp 9 has its opposite end provided with a transversely extending slot 11, which is substantially V-shaped for the major portion of its length and the rear wall of the slot 11 is curved inwardly adjacent one side of the clamp, to provide the cam surface 12, and the lower wall of the slot 11 is cutaway and 70 curved at a point adjacent the cam surface 12, as is shown at 13.

In use, when it is desired to clamp the rail 4 to the chair 1, the clamping member 9 is swung to the position shown in dotted lines 75 in Fig. 2, and the rail 4 mounted upon the raised portion 2, and engaged under the flange 5. The clamp member 9 is then swung to the position shown in Figs. 1 and 2, so as to cause the upper and lower walls 80 of the slot 11 to engage, respectively, over the adjacent flange of the rail and beneath the flange 7 formed on the adjacent end of the raised portion 2, further movement of the clamp 9 being prevented by virtue of the 85 rear wall of the slot 11 engaging against the adjacent edge of the flange 7, as shown in the drawings.

Having thus described my invention what I claim as new, is:

1. A device of the class described comprising a base, a raised portion formed on the upper side of the base at one end thereof, a rail supported by the raised portion and the base, a flange formed on one end of the 95 raised portion and adapted to engage one side of the rail base, the opposite end of the raised portion being provided with a flange, a clamping member pivotally associated with the base and having one edge thereof provided with a slot adapted when the clamping member is in operative position to receive the last-mentioned flange on the raised portion and one side of the rail base.

2. The combination with a base plate 105 adapted to support a rail and having a flange thereon for overlying one side of the rail, of a clamp pivotally associated with the base and having one end thereof provided with a transverse slot adapted when the clamp is in operative position to receive the flange on the base and one side of the 110

base of the rail, said clamp having the rear wall of the slot therein provided with a cam surface at one end of the wall and having the longitudinal lower edge of the wall of the slot curved at one end thereof and adjacent the cam surface on the inner wall of the slot, for the purpose specified.

In testimony whereof I affix my signature in presence of two witnesses.

JOHN W. BIRDSONG.
